UNITED STATES PATENT OFFICE.

ALBERT STEFAN COBENZL, OF HÖCHST, GERMANY.

PHOTOGRAPHIC DEVELOPING APPARATUS.

SPECIFICATION forming part of Letters Patent No. 609,661, dated August 23, 1898.

Application filed December 27, 1897. Serial No. 663,762. (No model.) Patented in England September 18, 1897, No. 21,482.

To all whom it may concern:

Be it known that I, ALBERT STEFAN COBENZL, chemist, residing at Höchst-on-the-Main, Germany, have invented new and useful 5 Improvements in the Manufacture of Photographic Developing Apparatus, of which the following is a specification.

This invention has been patented in Great Britain, dated September 18, 1897, No. 21,482.

o This invention has for its object to provide an apparatus whereby photographic negatives, &c., taken on a tour or otherwise may be developed and fixed without the use of a dark room.

5 Figure 1 is a longitudinal section of the apparatus. Fig. 2 is a detail.

The apparatus consists of a developing-tray A, covered on top for a portion of its length, to which end are connected inlet and outlet pipes a for the solutions, bent at right angles, and having a common filling and emptying mouth b, closed by a stopper, whereby the pouring in and out of the solutions may be effected without access of light. The tray is 5 inclosed by a hinged cover B, with flanged sides embracing those of the tray, this cover consisting for about two-thirds of its length of a frame fitted with superposed red and orange glass plates C D, forming a window for o lighting the interior of the tray and being fitted in sliding shutters and inclosed by a hinged lid E. The other part of the cover is domed and provided on its inclined side with binocular eyepieces F, covered inside with an 5 orange plate and closed by a sliding shutter G, which is only opened during observation. The bottom H consists of a red-glass plate covered by a hinged lid K. A sliding tube L may be fitted into the eyepieces to adapt them o to different persons. The under side of the cover B is preferably polished to reflect light into the tray.

The apparatus is used as follows: By means of a light-excluding sleeve the plate is introduced into the tray, the shutters of the window and eyepieces being closed, whereupon the developer is introduced in open light through the filling-orifice, and when it is desired to observe the progress of development o the slide of the window is drawn with one hand and the eyes are applied close to the eyepieces. The shutter of the sight-holes is

then opened with the other hand, whereby the operation can be sufficiently observed. When development is complete, the developer is 55 poured off and the fixing solution introduced, and after the time deemed necessary for fixing the plate can be removed.

Now, what I claim, and desire to secure by Letters Patent, is the following: 60

1. A photographic developing apparatus comprising a tray, a cover therefor having an opening for admitting light, two superposed glass plates of different colors covering said opening, and fitting in sliding shutters and 65 a lid hinged to the cover for screening said plates, substantially as described.

2. A photographic developing apparatus comprising a liquid-tight tray having its bottom composed of a colored-glass plate, an 70 opaque lid hinged to the outside of the tray and adapted to cover said bottom, a cover fitting the upper part of the tray and containing an opening, one or more removable colored-glass screens covering said opening, and 75 an opaque lid hinged to the outside of the cover for covering said screens, substantially as described.

3. In a photographic developing apparatus, the combination with a tray A having a glass 80 bottom H, lid K and pipes a, of a cover B hinged to said tray and carrying glass plates C, D, hinged lid E, and a dome provided with eyepieces F, substantially as described.

4. In photographic developing apparatus, 85 the combination with a tray, of a cover therefor having a domed portion, eyepieces on said domed portion, a hinged lid for the other portion, and colored-glass plates inside said eyepieces and under said lid, substantially as de- 90 scribed.

5. In a photographic developing apparatus the combination with a glass plate covering the top of it and a hinged lid having a light-reflecting under side substantially as de- 95 scribed.

In testimony whereof I have signed my name to this specification in the presence of two subscribing witnesses.

ALBERT STEFAN COBENZL.
